UNITED STATES PATENT OFFICE.

MONTAGUE H. ROBERTS, OF ENGLEWOOD, NEW JERSEY, ASSIGNOR TO FRANKLIN RAILWAY SUPPLY COMPANY, OF NEW YORK, N. Y., A CORPORATION OF DELAWARE.

DRIVING BOX.

Application filed September 9, 1924. Serial No. 736,678.

My invention relates to vehicle journal boxes suitable, especially, for the driving wheels of locomotives, and is concerned with a type of box wherein a bearing or crown structure separate from the rest of the box is removably secured therein. I aim to improve the behavior of such boxes in service by preventing pounding of the box in its guides and consequent loosening of the bearing structure in the box. How this and other advantages may be realized through my invention will appear hereinafter.

In the drawings, Fig. 1 is a side view of a locomotive driving box and associated parts conveniently embodying my invention, the various parts being shown in section to reveal the construction more clearly.

Fig. 2 shows a vertical section through the box, taken as indicated by the line 2—2 in Fig. 1.

Fig. 3 is in part a vertical section and in part a plan view of the structure shown in Fig. 1,—the section being taken as indicated by the line 3—3 in that figure.

The box shown in the drawings comprises a box structure 10 having at its sides or limbs 11 and 12 the usual flanges 13, providing grooves. The pedestal jaws 14 of the locomotive frame engage in these grooves and serve as guide-ways for up and down movement of the whole journal box. The box structure 10 is of a general yoke or U shape, with the U erect (right side up) about the axle 15, and its transverse member 16 a short distance beneath the axle. The structure 10 is supported by being suspended (as it were) from the separate crown bearing generally and comprehensively designated as 17, which rests on the axle 15 between the side members 11, 12. In the present instance, the bearing 17 comprises two parts 18 and 19, divided along a cylindrical surface concentric with the axle 15, and provided with accurately interfitting engagement means (Figs. 1 and 2) consisting of a low ridge 18^a on the lower part 18 and a corresponding shallow groove 19^a in the upper part 19. Preferably, the part 18 is of brass or other bearing metal and the part 19 of more rigid material, such as steel. A bottomless sheet metal lubricator device or cellar 20 (shown as of the general Elvin type) is arranged in the box structure 10 beneath the axle 15, and

its follower plate 21 is urged upward toward the axle by a spiral compression spring 22 beneath it that is partly accommodated in a recess 23 in the member 16. Ridges 24, 25 on the box sides 11, 12 reduce the friction when the cellar 20 is inserted or removed. At one end, the follower plate 21 has a downward projecting indicator rod 26 that normally lies in a vertical slot in the transverse member 16. The cellar 20 may be secured in place by means of a horizontal retainer bar or rod 27 extending through engagement means in the form of apertured lugs 28, 28 (on the members 11, 12) across the yoke opening at the inner end of the box 10, and it is secured in place by one or more keys 29.

Shoulders 30 extend inward from either side 11, 12 of the box structure 10 at its upper end, and the bearing 17 has corresponding shoulders 31 which cooperate with the shoulders 30 in the support of the box structure 10 by the bearing 17. The bearing 17 is of such general width as to fit (snugly but not tightly) between the sides 11, 12 below the shoulder 30, while its upper portion is of such reduced width as to fit (snugly but not tightly) in the opening between the shoulders 30: i. e. the bearing corresponds substantially to the internal width of the box 10. At the lower end of the bearing 17, on either side, is a central downward projecting lug 32 adapted to engage and fit snugly in a recess 33 in the ridge 24 on the corresponding side member of the box structure 10, so as to prevent movement of the bearing 17 in the box structure lengthwise of the axle 15. Lubricant from the cellar 20 and the axle 15 is supplied to the outer surfaces of the box 10 (to lubricate its up and down movement) through the clearances between the lower surfaces of the lugs 32 and the bottoms of the recesses 33, and through corresponding holes 34 in the box sides. Removable tapering pins or key members 35 are normally engaged between the shoulders 30, 31 to wedge the bearing 17 fast in the box structure 10 and maintain the lower ends of the bearing firmly seated against the shoulders formed by the upper sides of the ridges 24, with the lugs 32 engaged in the recesses 33. The adjacent faces of the shoulders 30, 31 are concave, and the opposite sides of

the wedges 35 are correspondingly convex, and the faces of the shoulders 31 are inclined in correspondence with the taper of the wedges, as shown. The wedges 35 may be 5 powerfully forced home and held in place by tightening up nuts 36 on bolts 37 that extend through laterally projecting apertured lugs 38 on the ends of the wedges. The heads 39 of the bolts 37 lie in under-cut recesses at the inner ends of grooves in the side members 11, 12 of the box structure 10.

The load or weight of the locomotive may be transmitted to the bearing 17 in various ways: in the present instance, it is freely 15 received by the bearing 17, independently of the box structure 10, through the opening between the shoulders 30, 30 of the latter. As shown in Fig. 2, the bearing 17 has recesses 42, 42 in its upper side for receiving 20 corresponding projections. The box structure 10, therefore, is entirely unloaded as respects the vehicle weight, but engages the vehicle frame and the bearing 17, keeps the bearing 17 in position, and receives and 25 transmits to the frame the side thrust from the wheel. The bearing 17 also transmits the horizontal "fore and aft" thrust from the journal or shaft 15 to the locomotive frame 14 through the box structure 10, as 30 well as stresses due to the tendency of the bearing to turn with the shaft. Such stresses, however, are transmitted separately and 35 independently of the weight (at right angles thereto), so that the weight has no component tending to spread the box sides.

The outer faces 43, 44 of the box structure 10 and the bearing 17 are flush with one another, and afford lateral bearing surfaces 40 for engaging the driver wheel hub (not shown) and taking the side or "end" thrust from the wheel. Since this bearing surface is on both of the parts 10 and 17 and extends all the way around the opening for the shaft 15, it is of greater area than heretofore 45 possible in standard practice, so that the pressure is more widely distributed, and the wear will be more uniform and not be so great. The thrust bearing surfaces 43, 44 are kept accurately in alignment by the engagement of the lugs 32 in the recesses 33 and by the wedges 35. These bearing surfaces 43, 44 may consist of Babbitt facings 50 or linings on the parts 10 and 17, as shown.

It will be seen that in order to remove the 55 crown bearing 17 from the journal box 10, it is only necessary to relieve the bearing of the spring tension and lift the spring saddle (not shown) out of engagement with its recesses 42, 42, withdraw the wedges 35, and 60 drop the box sufficiently to disengage the bearing 17 therefrom at 32, 33. Having been disengaged from the box 10 by vertical displacement therein as just described, the bearing 17 may be removed from the box by 65 simply moving the bearing lengthwise of the

axle 15. When the box structure 10 is to be removed from the locomotive frame in order that its hub face 43 may be relined (or for any other reason), it is only necessary to remove the bearing 17 as just described, drop the frame pedestal binder 46 so as to open the lower ends of the guideways 14, and allow the box structure 10 to slide or drop down from the axle 15,—the opening between the shoulders 30, 30 at the upper end 70 of the box structure being of width sufficient to pass the shaft readily, though of less width than the bearing 17 as a whole. No drop-pit crane is required for removal of any or all the bearing parts, as just described; neither is it necessary to drop the wheels or to lift the locomotive as a whole 75 from its frame for such purposes.

In the light of this explanation of the general box construction here illustrated, the following description of the features 80 with which my present invention is more especially concerned will be easily understood.

In order to keep the box 10 always tight in the pedestal jaws 14, 14 and prevent loosening of the bearing 17 in the box by pounding of the latter in the jaws, an automatic tightening device may be provided, here shown as comprising an adjustable wedge 50 adjacent the inclined face of one of the jaws 14 and a floating wedge 51 between said wedge 50 and the corresponding side of the box 10. The wedge 50 has a stem or bolt 52 which extends down through a hole 53 in the pedestal frame binder 54. The spring casing 55 is rotatably mounted in a double armed bracket 56 secured to said binder 54. Helical compression springs 57, 57 act between the bottom of the casing 55 and an abutment nut 58 threaded on the bolt 52, and having ears or lugs 59 engaged in corresponding slots in the casing 55. This automatic wedge device, it will be seen, corresponds in construction substantially to that shown in U. S. Patent No. 1,492,824, granted May 6th, 1924, to William E. Woodard and Frederick W. Martin.

When the locomotive frame and the jaws 14, 14 start to move downward relatively to the box 10, the inclined surface of the wedge 50 moves away from the abutting inclined surface of the wedge 51, thus relieving the tightness slightly and obviating any tendency for the box to stick. When the jaws 14, 14 arise again, a reverse action takes 115 place. The exact degree of tightness generally maintained by the wedges 50, 51 is determined by the tension of the springs 57, which may be adjusted by rotating the casing 55 by its reduced lower hexagonal end, 120 so as to screw the abutment 59 up or down on the bolt 52.

It will be seen that the action of the automatic tightening device prevents loosening or pounding of the box 10 in the jaws 14, 14, 125

and effectually obviates any tendency for the bearing 17 to become loose in the box, or to hammer and distort the latter or its part 18. This is particularly important in cases where the load of the vehicle weight is transmitted to the bearing 17 independently of the box proper 10 (as in the present instance) so that the bearing 17 is held rigidly in position on the shaft 15 and cannot readily give with any slight pounding motion of the box 10 in the jaws 14, 14. With such independent fixity of the bearing 17, hammering or pounding between it and the box 10 would otherwise tend to be severe and troublesome.

I claim:

1. The combination with box guides, a yoke-shaped box open at its top, and an axle bearing removably secured in said box, of a self-tightening wedge device for preventing pounding of the box in the guides and

consequent loosening of the bearing in the box.

2. The combination with box guides, a box in said guides, and an axle bearing removably secured in said box receiving the load of the vehicle weight independently of the latter, of a self-tightening wedge device for preventing pounding of the box in the guides and consequent loosening of the bearing in the box. 25

3. The combination with box guides, a yoke-shaped box open at its top having a pair of shoulders on its side, and an axle bearing wedged between said shoulders, of a self-tightening wedge device for preventing pounding of the box in the guides and consequent loosening of the bearing in the box. 30

In testimony whereof, I have hereunto signed my name.

MONTAGUE H. ROBERTS.
